UNITED STATES PATENT OFFICE.

ELLSWORTH E. CIPPERLY, OF PALO ALTO, CALIFORNIA.

HEADLIGHT.

Application filed June 29, 1925. Serial No. 40,322.

To all whom it may concern:

Be it known that I, ELLSWORTH E. CIPPERLY, a citizen of the United States, and a resident of Palo Alto, in the county of Santa Clara and State of California, have invented a new and useful Improvement in a Headlight, of which the following is a specification.

The present invention relates to improvements in headlights for motor vehicles and the like, and its particular object is to provide a headlight arrangement in which the light itself is hidden behind an opaque front cover so that no direct rays emanating from the source of light are projected forwardly.

It is further proposed to provide a flat reflector above the light on an incline allowing rays of light emanating from the source to be reflected in a forward and downward direction so as to strike the road pavement for illuminating the same without striking the eyes of the driver of an approaching automobile.

It is further proposed to arrange the source of light relative to the reflector in such a manner that all the rays projected from the source, except those within the area of the reflector, are intercepted.

It is further proposed to limit the beam issuing from the reflector to a rectangular cross section whereby particularly the upper line of light is clearly defined.

It is further proposed to provide means whereby the angularity of the reflector relative to a horizontal plane or to the road pavement can be adjusted.

Further objects and advantages of my headlight will appear as the specification proceeds.

The preferred form of the invention is illustrated in the accompanying drawing, in which

Figure 1 shows a front view of my headlight with a portion of the glass cover cut away.

Figure 2 a vertical section taken along line 2—2 of Figure 1, and

Figure 3 a horizontal section taken along line 3—3 of Figure 2.

While I have shown only the preferred form of the invention, I wish to have it understood that various changes or modifications may be made within the scope of the claim hereto attached without departing from the spirit of the invention.

In the device shown in the drawing, I

have selected a cylindrical housing 1 as probably being best adapted for use in connection with my light arrangement, but it should be understood that any other suitable form may be substituted provided it leaves sufficient room for the interior arrangement forming part of my invention. An opaque disk 2 may be secured to a flange 3^a projecting inwardly from the front edge of the housing by means of screws 4 or in any other suitable manner. The disk 2 is preferably made of metal and is provided with a rectangular light opening 3 occupying substantially the central portion of the disk. The latter supports a box 7 comprising a bottom 8 made substantially flush with the bottom line of the opening 3 and being substantially coextensive in width with the opening, the two sides 9 being somewhat higher in front than the height of the opening and slanting downwardly toward the rear, and a rear wall 11 having a downward extension, as shown at 12, in which is mounted a lamp socket 13 in such a manner that a lamp 14 engaged therewith is disposed substantially centrally below the bottom 8 of the box. To the top of the rear wall is hinged, as shown at 16, a flat reflector 17 preferably of rectangular form and of a width corresponding substantially to the width of the box, and of a length corresponding substantially to the length of the top edges of the sides so that the reflector would normally assume the slanting position shown in Figure 90 2, with its front edge resting against the rear face of the disk 2. The position of the reflector may, however, be adjusted by means of a screw 18 held in the rear wall of the light housing with freedom of rotary motion but against endwise motion and threadedly engaging a socket member 19 pivoted to the back of the reflector as shown at 21. It will be seen that when the screw is turned from the outside of the light housing, the slanting position of the reflector will be changed.

The bottom of the box 7 is provided with a central circular opening 22 substantially above the source of light, the opening being enlarged by two parallel slots 23 and 24 arranged to allow the rays of light emanating from the lamp 14 to strike the entire surface of the reflector while all the rays lying outside of the transverse plane of the reflector are intercepted.

A glass 26 may be secured in front of the

opaque disk 2 in a manner illustrated in Figure 2, that is, by means of individual clips 27 secured on the edge of the glass and a ring 28 flanged to engage with the clips and 5 adapted to be pushed over the end of the rim of the light housing, as shown at 29, with a rubber ring 30 interposed between the disk 2 and the clips.

10 The advantages of my construction are apparent from the foregoing description.

15 No rays emanating directly from the light strike the pavement or the eyes of an approaching driver or pedestrian. The only light rays that become active are those passing through the opening in the bottom 8 and they strike the reflector and are reflected against the pavement in a downward direction so that they light the pavement where the latter should be lit without blinding the 20 eyes of an approaching driver. The beam of light emanating from the reflector is further controlled and clearly defined by the rectangular opening in the disk 2. It will be noted that the top and bottom edges of

the opening in the disk are somewhat below 25 the top and bottom edges of the reflector which is of particular importance as far as the top edge is concerned, because any light rays which might be reflected from the top portion of the reflector in such a manner as 30 to strike the eyes of an approaching driver, are intercepted by the top edge of the opening.

I claim:

35 In a headlight, a vertical opaque front plate formed with a rectangular opening therein, a flat reflector mounted behind the plate on an incline so as to project light rays through the opening and a light mounted behind the front plate below the opening and 40 positioned below the reflector to allow light rays emanating therefrom to strike the reflector with a plate interposed between the light and the reflector abutting the front and perforated to allow light rays to pass 45 therethrough from the light to the reflector within the area of the latter only.

ELLSWORTH E. CIPPERLY.
